Claims priority, application Great Britain Apr. 5, 1957

6 Claims. (Cl. 114—74)

This invention relates to water-borne tankers, particularly ocean-going tankers, for the transport in liquid form, at low temperature and approximately atmospheric pressure, of substances which are normally in a gaseous state. The gas which comes mainly into question is methane, but the references herein to methane are, wherever the context allows, to be read as references also to like gases which it may be desirable to transport in the liquid state.

The carriage of liquid methane by ship poses several problems due to the fact that the density of liquid methane is very low compared with that of water, and that the methane must be insulated from ambient heat to prevent excessive evaporation. From the point of view of insulation, it is best for all the methane tankage to be below deck, but such a vessel would have an undesirably high freeboard. This difficulty can be cured in some respects by the provision of additional tanks supported on the deck of the ship, but although this reduces the freeboard to a workable level and allows the methane-capacity of the ship to be increased, such deck tanks require very special supporting means to retain them firmly in position on a rolling deck, and also require special insulation from ambient heat due to their exposed position. This is particularly troublesome in a tanker of, say, 16,000 tons which has to operate in rough seas and in hot climates.

An object of the present invention is to enable a methane tanker to carry as much methane as possible and, at the same time, avoid the disadvantages given above.

According to the present invention, there is provided a marine tanker for the bulk transport in the liquid state at low temperature of methane (or like ordinarily-gaseous substances), wherein the cargo tanks comprise a plurality of main tanks disposed in a closely-spaced row along the fore-and-aft centre line of the ship which main tanks are of circular cross-section in plan and extend at their widest parts for substantially the full width of the ship, together with comparatively small wing tanks provided in the spaces between the main tanks toward the sides of the ship, and wherein the wing tanks are wholly below the main deck while the main tanks have portions of reduced diameter which extend up through the main deck the protruding portions of the main tanks being enclosed in a longitudinally-extending turret structure above the main deck.

In this way a kind of turret ship is formed, and this construction provides several advantages. The entire methane tankage is below deck so that it can be insulated more effectively, and the problem of supporting tanks on the deck is removed. At the same time, the freeboard is not raised to an unworkable level, and the handling qualities of the ship are not impaired.

The tops of the main tanks may have narrow necks projecting up through the turret, and, when loaded, each tank is ordinarily kept topped up to a level within the narrow neck. This means that, under normal working conditions, the liquid-free surface in each tank will not be so large as to affect adversely the stability and control of the ship, particularly in rough seas.

The above and other features of the invention will be apparent in the following description, given by way of example, of one embodiment in accordance with the invention, reference being had to the accompanying drawings in which:

2

FIGURE 1 shows in elevation a marine tanker for the transport of methane,

FIGURE 2 is a plan showing the arrangement of the methane tanks in the holds,

FIGURE 3 is a further plan showing the arrangement of tanks at main deck level, and

FIGURES 4 and 5 are transverse views partly in section seen on the lines 4—4 and 5—5 respectively of FIGURE 3.

Referring firstly to FIGURES 1 and 2, the cargo-carrying section of the tanker hull 10 is divided into six separate main hold compartments 11 to 16 by a series of transverse bulkheads 17. Disposed individually in the hold compartments 11 to 16, in a closely-spaced row along the fore-and-aft centre line of the vessel are six heavily-insulated main cargo tanks 18 and 23. The tank insulation is shown at 60 in FIGURE 4. These main tanks are, for the most part, substantially cylindrical in form with their principal axes vertical, and in general they extend at their widest parts for substantially the whole width of the vessel although tanks 19 and 23 are somewhat less in diameter than tanks 20, 21 and 22, and the most forward tank 18 is a good deal less still in diameter.

The vessel is of turret construction, that is to say it has a main deck at the level 24 and a narrower turret deck above at the level 25. Each of the main tanks 18 to 23 extends up through the main deck at level 24, and, with the exception of the tank 20, the portions of the tanks that protrude above the main deck are as large in diameter as can be conveniently accommodated within the turret structure 26. To this end, tanks 19, 21, 22 and 23 have stepped-in upper portions 28, 29, 30 and 31, but the forward tank 18, being already relatively narrow, does not need to be stepped in. Each of the six tanks terminates at its upper end in a narrow neck 27 surmounted by a pump motor housing 32. In the case of the five tanks 18, 19, 21, 22 and 23 the narrow tank neck 27 reaches up through the turret deck at level 25 and the housing 32 is situated on said deck, but the tank 20, for reasons which need not be discussed here, is not as high as the other five, having its neck 27 terminating only just above the main deck level 24 and its pump motor housing 32 disposed on the main deck within the turret structure.

Owing to the circular plan form of the main tanks 18 to 23, there is an appreciable space below decks between one tank and the next at opposite sides of the vessel, and in the case of tanks 19 to 23 these spaces between are utilised by disposing in them eight additional insulated wing tanks 33 of much smaller capacity bearing insulation 61 (FIGURE 5). The wing tanks 33 are all cylindrical with their principal axes upright, and are located wholly below the main deck level 24. As will be seen in FIGURE 2, the arrangement of bulkheads between the main tanks 19 to 23 is such that each wing tank 33 has its own individual water-tight hold compartment 34, each of the bulkheads 17 branching, as it were, into two diverging bulkheads 35 to embrace a wing tank as it approaches each side of the hull.

It will be observed that each of the small wing tanks 33 has a diameter only about one-fifth the beam of the ship, and, as can be seen in FIGURE 3, the turret structure 26 and turret deck 25 have a width which is about 60% of the ship's beam. In a typical example of a 16,000 ton deadweight methane tanker, the largest main cargo tanks might have a capacity of the order of 280,000 cubic feet, and the wing tanks a capacity of 9,000 cubic feet each. In a vessel of this order of size the turret width of approximately 60% of the beam affords a working deck on either side that is wide enough for easy working.

As can best be seen in FIGURE 3, the spaces within the turret structure 26 and between the portions of the main cargo tanks lying therein, are occupied by a cargo lique-

faction plant and by tanks 80 on the main deck. Thus there tanks 80 between the pairs of methane tanks 18 and 19, 21 and 22, and 22 and 23, with an additional smaller tank beyond the aft methane cargo tank 23, while between the cargo tanks 19 and 21 and over the methane cargo tank 20 there is a further large tank 80. Despite the heavy insulation of the methane cargo tanks, there will be a certain amount of methane boiling off in them during a voyage, and gaseous methane drawn off from the tanks can be reliquefied so that it can be returned to the tanks and the liquid level kept up. Each main tank 18 to 23 is normally kept topped up so that the liquid level is in the comparatively narrow neck 27, whereby both the free liquid surface area for evaporation, and the liquid-free volume, in each tank are kept as low as possible.

The deck tanks 80 will contain oil cargo or water ballast and be connected to the ship's normal ballast and cargo oil lines. Their position high up in the ship enables these tanks to be used to control stability so that the ship will have an easy motion in rough seas. The deck tanks 80 can also be employed for flooding the hold space around the cargo tank in the event of the tank springing a leak, whereupon the oil or water ballast flooding the hold will freeze around the leak and stop it. The ballast tanks 80 are simply constructed of welded plate, and are rectilinearly-shaped as shown in FIGURE 3, being multi-sided so as to best fill the available spaces.

In addition to the methane cargo tanks, and the deck tanks 80, the vessel also has, besides further conventional ballast which will not be described in detail, a number of deep tanks 82, 83. The deep tanks 82 are in the fore part of the ship, grouped around the fore-most methane tank 18, while the tanks 83 are grouped around the aft methane tank 23. The deep tanks 82, 83 may be filled with water ballast, but preferably they are used for the transport of an oil cargo, in addition to the liquid methane cargo. In a ship of 16,000 tons deadweight these tanks together with the deck tanks 80 can carry about 9,300 tons of oil cargo, which is a valuable supplement to the liquid methane cargo.

I claim:

1. A marine tanker for the bulk transport of liquid methane at low temperature and substantially atmospheric pressure comprising the combination of a hull, a main deck, a plurality of transverse bulkheads dividing up the cargo space below the main deck into a plurality of separate main hold compartments, a turret deck narrower than the main deck and extending fore-and-aft above the main deck over all said hold compartments, a plurality of externally-insulated main tanks for liquid methane cargo, said tanks being disposed in a closely-spaced row one in each of the hold compartments and each tank being stepped in at at least one level near the top thereof so as to give the tank a narrow neck portion with the full-width portion of the tank disposed wholly below the main deck and the narrow neck portion projecting above the main deck and lying within the confines of the portion of the deck width defined between the sides of the turret deck, and a plurality of smaller externally-insulated wing tanks for liquid methane cargo said wing tanks being disposed wholly below the main deck in wing spaces between the main tanks toward the sides of the ship and said transverse bulkheads being formed around said wing tanks to enclose each wing tank in its own separate wing hold compartment.

2. A marine tanker for the bulk transport of liquid methane at low temperature and substantially atmospheric pressure comprising the combination of a hull, a main deck, a plurality of transverse liquid-tight bulkheads dividing up the cargo space below the main deck into a plurality of separate main hold compartments, a turret deck narrower than the main deck and extending fore-and-aft above the main deck, a plurality of externally-insulated main tanks for liquid methane cargo each

having a configuration that is mainly of upright cylindrical form, said tanks being displaced in a row one in each of the hold compartments and each tank being stepped in at at least one level near the top thereof so as to give the tank a narrow neck portion, and a plurality of smaller externally-insulated wing tanks for liquid methane cargo, said wing tanks being disposed wholly below the main deck in wing spaces between the main tanks toward the sides of the ship and said transverse bulkheads being formed around said wing tanks to enclose each wing tank in its own separate wing hold compartment.

3. A marine tanker for the bulk transport of liquid methane at low temperature and substantially atmospheric pressure comprising the combination of a hull, a main deck, a plurality of transverse liquid-tight bulkheads dividing up the cargo space below the main deck into a plurality of separate main hold compartments, a turret deck narrower than the main deck and extending fore-and-aft above the main deck in uninterrupted manner over all said hold compartments, turret side structure enclosing the space between the main and turret decks, a plurality of externally-insulated main tanks for liquid methane cargo each having a configuration that is mainly of upright cylindrical form and occupies at its widest part substantially the whole available width of the vessel, said tanks being disposed in a closely-spaced row one in each of the hold compartments with their upright axes intersecting the fore-and-aft centre line of the vessel and each tank being stepped in at at least one level near the top thereof so as to give the tank a centrally-placed narrow neck portion with the full-diameter portion of the tank disposed wholly below the main deck and the central neck portion projecting above the main deck and lying within the confines of the portion of the deck width defined by the turret structure, at least some of said main tanks having between the neck and the full-diameter portion a stepped section of an intermediate diameter which intermediate diameter stepped section commences just below the main deck but is otherwise located wholly within the turret structure and of a diameter as large as the enclosed space within the turret structure will allow, those tanks with an intermediate diameter section having their narrow neck portions projecting up above the level of the turret deck, a pump housing disposed over each tank neck, and a plurality of smaller externally-insulated wing tanks for liquid methane cargo each having a substantially upright cylindrical configuration, said wing tanks being disposed wholly below the main deck in wing spaces between the main tanks toward the sides of the ship and said transverse bulkheads being formed around said wing tanks to enclose each wing tank in its own separate wing hold compartment.
4. A tanker as claimed in claim 2, wherein at least some of the main tanks each have, between the neck and the full diameter portion, a stepped section of an intermediate diameter, which stepped section commences just below the main deck but is otherwise located wholly within the turret and of a diameter as large as the space within the turret structure will allow.
5. A tanker as claimed in claim 4, wherein deck ballast or oil cargo tanks are disposed in the turret between the intermediate diameter sections of the cargo tanks.
6. A tanker as claimed in claim 2, wherein the wing tanks are of upright cylindrical form and each has a diameter approximately one fifth of the beam of the ship.
